UNITED STATES PATENT OFFICE.

GASTON STROBINO, OF PATERSON, NEW JERSEY.

PHONOGRAPH-REPRODUCER.

1,374,479.

Specification of Letters Patent. Patented Apr. 12, 1921.

Application filed March 5, 1920. Serial No. 363,367.

To all whom it may concern:

Be it known that I, GASTON STROBINO, a citizen of the United States, residing at Paterson, in the county of Passaic and State 5 of New Jersey, have invented certain new and useful Improvements in Phonograph- Reproducers, of which the following is a specification.

In the ordinary phonograph machine the 10 membrane or diaphragm is arranged in a suitable mounting and the stylus is fulcrumed on the mounting and has one end in contact with the membrane and the other end resting on the undulatory surface or 15 groove of the record, the fulcrumed stylus being held normally in a definite relation with reference to the membrane by springs; in other words, the stylus acts on the membrane after the manner of a lever which ob- 20 tains its purchase or is mounted on the mounting for the membrane. On account of this effect of a lever which thus characterizes the stylus it must be positioned with reference to the undulations when op- 25 erating so that they can cause the movement thereof around its fulcrum that produce vi- 30 brations of the membrane. There are two genera classes of records used in phonograph machines—those whose grooves have their undulations “vertical”, or up and down, and those whose grooves have their undulations lateral,—wherefore a machine having a reproducer or reproducing means 35 designed for one class of records cannot be made to reproduce properly from records of the other class.

One of the principal objects of this in- 40 vention is to provide a reproducer which will coöperate with records having either vertical or lateral undulations and faithfully reproduce sound. To this end the present invention broadly consists in a repro- 45 ducer for phonographs or similar machines embodying certain novel features of construction and arrangement of a vibratory membrane member and a free stylus device or foot-piece rigidly secured to and projecting from a vibratory part of said mem- 50 ber, in combination with means, mounted on the bed or other fixed support, to hold the reproducer in operative relation to a record to be reproduced when the stylus device is made to rest on the record. By “free stylus” I exclude styluses that trans-

mit vibrations to the membrane only by 55 being fulcrumed or having a purchase on some non-vibratory part, such as the mount- ing for the membrane.

To obtain equally good sound-reproducing results with the improved mechanism, 60 regardless of the class of record with which it is made to coöperate, it is best to employ with the particular record at any time being used the kind of needle that is specially adapted therefor, for instance, the needle 65 that operates best with the V-shaped lateral groove, or that which operates best with the V-shaped vertical or that which operates best with the U-shaped vertical groove; provision is therefore made in the best form 70 of the invention for interchangeability of needles or stylus points in a novel way hereinafter to be pointed out.

In the accompanying drawings,

Figure 1 is a front elevation of the re- 75 producer, showing it in operative position on a record;

Fig. 2 is a side elevation of what is shown in Fig. 1, certain parts appearing in sec- 80 tion;

Fig. 3 is a plan; and

Figs. 4, 5 and 6 show a modified form of the reproducer. *a* designates the bed or support of the phonograph machine, in which is arranged to rotate the suitably 85 driven spindle *b* for supporting the platen *c* on which a record *d* may be placed.

The membrane member is preferably though not necessarily that shown in the drawings, where *e* is a hollow body having 90 a relatively large mouth and formed of thin sheet material, such as parchment, paper or the like, the same being here shown as generally truncated-conical with its mouth or larger end elliptical in form and preferably 95 bound or finished with a hoop *f* of suitable thicker reinforcing material and its smaller end closed; the hoop has a narrow groove *g* into which the edge of the material of the body *e* may be fitted and glued. The hoop 100 need not necessarily be continuous; thus in Figs. 4 and 5 it is shown in two parts, the material *e* being reinforced where the splits in the hoop come by fabric *h* cemented thereto. The hoop is a vibratory part of 105 the membrane member, though it is also a frame or reinforcing and shape-maintaining element for its (also vibratory) portion *e*,

The stylus device as herein illustrated by way of example is constructed as follows: A fork *i*, which is preferably though not necessarily formed so as to be quite sensitive to vibrating influence, as by being composed of brass and having its arms tapering and extending laterally in opposite directions, has means on the ends of said arms, as shoulders *j* and nuts *l*, to clamp the membrane member thereto, the said arms preferably penetrating the hoop portion *f* of the membrane member at points coincident with its greatest diameter; and depending from the crotch portion of the fork is a fitting *m* having a stem *n*, with a nut *o* screwed thereon, to bind said fitting to the fork. The arms may with advantage be formed tubular, both to lighten them and increase the vibratory action thereof. There is also a needle or stylus-point holder *p* rotative with a fairly tight fit on a horizontal axis in the fitting and apertured radially at a plurality of points to receive the needles, *g*, particularly adapted to different specific forms of grooves, as hereinbefore indicated; this holder is adapted to be turned to position any of the needles in operative relation to the record. A part of the stylus device may also be the coupling piece *s*, here shown of stiff material, secured to the fork on the one hand and to the membrane member on the other in any suitable way; this element, however, is but an accessory to prevent dislocation of the membrane member and stylus device where the former is jointed to the latter at the ends of the arms of its fork, as in the handling incident to withdrawing and replacing the reproducer when changing records, or due to the tendency of the stylus device to run ahead of the membrane member under the influence of the rotating record, although in effect it amounts to a third arm of the stylus device rigidly secured to a vibratory part of the membrane member.

The means to hold the membrane member upright over the record to be reproduced while supported by its stylus device on the record is constructed, according to the example shown, as follows: In a bracket *t* secured to bed *a* and provided with a ball-bearing *u* and a centering pin *v* is swiveled on a vertical axis (between the ball-bearing and centering pin) an arm *w*, and in this arm is pivoted, on a horizontal axis, the clip *x*, which may have any desired form (compare Figs. 1 and 4) and is rigidly secured to the membrane member. This means, while keeping the membrane member upright, allows it to bear by its own weight on the rotating record and also to progress generally radially of the record in response to the tendency of the spiral formation of the grooves of the record thus to advance it.

y is a handle for manually shifting the reproducer to and from operating position; and *z* a pad on the bed *a* on which the stylus point may rest when the reproducer is not operating.

My reproducer has been used with equally good results whether the record employed have vertical or lateral groove undulations, especially if that needle or stylus point be made to coöperate with the record which is particularly suited to the cross-sectional form of the groove which the record presents. Its adaptability to reproduce sound faithfully whether the record-groove undulations are vertical or lateral is fundamentally due to the stylus device not being confined, as in the ordinary reproducer, to a plane of movement around a pivot, and also, in the best form of the invention, to these contributing factors, to wit: That the membrane member is a hollow body having a relatively large mouth and that the stylus device is a slender member attached at one end to the membrane member in the line of its greatest circumference and having its other end adapted to rest on the record; that the stylus device is a fork secured as to the arms thereof and only at the ends of said arms to a membrane member in the line of substantially its greatest circumference; and that each fork end of the stylus device extends laterally, so that it is maintained while operating in a state of tension incident to the weight of the membrane member.

When the hoop is split as in Figs. 4 and 5, the sound is amplified, because at the extreme of each half of the hoop the vibration is greater than if the hoop were intact at the point of breach.

Yielding washers *k* are shown in Fig. 1 between shoulders *j* and nuts *l*; they are not indispensable and may be omitted entirely, especially where the hoop is split and can therefore yield (by expanding or contracting) diametrically to suit the effective span of the fork *i* in assembling the membrane member and stylus device.

If there is found to be excessive spring in the structure formed by the membrane member and stylus device (so that in reproducing from lateral cut records there will be a too-violent springing back of the stylus point following some extreme deflection thereof, with perhaps a resulting harshness in the sound produced) a brace *2*, shown in Fig. 4, may be provided.

Having thus fully described my invention, what I claim is:

1. In combination, a reproducer including a vibratory membrane member and a forked-shaped free stylus device rigidly secured as to the arms of its fork and only at the extremities of said arms to said member

in the line of substantially its greatest circumference, and means to support the reproducer in operative relation to a record.

2. The hereindescribed reproducer membrane member including a membranous body having substantially coincident with its greatest circumference a reinforced edge portion, in combination with a stylus device rigidly secured to said edge portion.

3. The hereindescribed reproducer membrane member including a hollow membranous body formed with a relatively large mouth and having substantially coincident with its greatest circumference a reinforced edge portion, in combination with a stylus device rigidly secured to said edge portion.

In testimony whereof I affix my signature.

GASTON STROBINO.
